UNITED STATES PATENT OFFICE.

HARRY B. RANDALL, OF UNION CITY, PENNSYLVANIA.

WOODWORKING-MACHINE.

No. 923,704.

Specification of Letters Patent.

Patented June 1, 1909.

Application filed April 10, 1908. Serial No. 426,287.

To all whom it may concern:

Be it known that I, HARRY B. RANDALL, a citizen of the United States, residing at Union City, in the county of Erie and State 5 of Pennsylvania, have invented new and useful Improvements in Woodworking-Machines, of which the following is a specification.

This invention relates to wood working 10 machines, and consists in certain improvements in the construction thereof as will be hereinafter fully described and pointed out in the claims.

The machine is specially designed for 15 forming patterns on the surfaces of blanks, such for example, as chair seats.

In the exemplification of the invention illustrated the machine is designed to form chair seats having a scoop and saddle pattern therein.

In carrying out the invention I utilize an endless carrier with automatic clamps on which the blanks may be placed as the carrier moves, the clamps automatically engaging 25 the blanks holding them in place. The endless carrier then travels under knives or other devices which are operated to and from the carrier to form upon the blank the desired pattern. After the blank has passed 30 under the device for forming the pattern, the clamps are automatically loosened and the seat discharged. The endless carrier travels in one direction and permits of a continuous travel to different instrumentalities, the blanks being laid successively upon 35 the carrier.

The invention is illustrated in the accompanying drawings as follows: Figure 1 shows a plan view of the discharge or back end of 40 the machine. Fig. 2 a plan view of the front end of the machine. The part shown in Fig. 1 being a continuation of the part shown in Fig. 2. Fig. 3 is a section on the line 3-3 in Fig. 1. Fig. 4 a section on the line 4-4 in Fig. 4. Fig. 5 a detail view of 45 one of the automatic clamps. Fig. 6 a section on the lines 6-6 in Figs. 2 and 4. Fig. 7 a detached view of one of the sections of the carrier. Fig. 8 a vertical section of a 50 roll and a fragment of pattern track. Fig. 9 a side elevation of the machine.

1-1 mark the side frames of the machine. These are supported by the legs 2 and braced by the cross bar 3. They are provided with 55 the V shaped guide ways 4 in their upper edges which support the endless carrier 5.

The carrier is made up of the sections 6 which are connected together by the hinges 7, and each section is provided with the V shaped guide ways 8, which is adapted to 60 run in the V shaped groove 4 in the frame, so that the carrier is not only supported and maintained in a proper position vertically, but is also made to travel in a straight line horizontally by means of the grooves and 65 guides.

The carrier runs over the sprockets 9 and 10, the sprocket 9 being at the rear end of the machine, and the sprocket 10 at the front end of the machine. These sprockets 70 are preferably shaped with each face being of sufficient length to accommodate a section 6. They are mounted on the shafts 11 and 12 respectively. The face of each sprocket is notched at 18 and each of the sections 6 75 has a V shaped projection 14 which enters the notch 13 to assure a proper driving of the carrier, and a proper registering of the sections on the sprocket.

At the proper intervals along the carrier 80 clamping blocks 15 are provided against which the blanks are placed, these clamping blocks are carried by the posts 15^a and may be adjusted and locked in position by the set screw 15^b. Side gages in the shape of pins 85 15^c are provided. These pins are secured in the slots 15^d so that they may be adjusted for slight variations in sizes of blanks. The automatic clamp 16 is carried by bell crank lever 17, the bell crank lever being pivoted 90 at 18 upon an arm or lug 19 extending from the bottom of section 6. In Fig. 4 a blank 20 is shown in place between the clamping blocks 15 and automatic clamp 16. A weight 21 is secured to the front end of the 95 lever 17, and this weight engages a cam 22 as the carrier turns on the sprocket. This cam lifts the weight so as to open the clamp as the carrier turns on the sprocket. The blank can then be put in place and the weight 21 100 moves off the cam so that the clamp engages the blank and securely holds it before it reaches any of the cutters. A similar cam 23 is arranged in the path of the lever at the rear end of the machine and automatically 105 lifts the weight 21, and consequently operates the clamp to open it as the blank reaches the rear of the machine, so that the blank is removed or discharged as the carrier moves over the sprockets 9.

In the machine shown the tools employed are a cutter 24 which is shaped to cut the

scoop of the seat. The cutter 25 which is designed to form the front or saddle part of the seat; a sander 26 of the same shape as on cutter 24 to sand the scoop of the seat; a sander 27 to sand the saddle portion of the seat; a sander 28 similar in shape to the sander 26 but ordinarily of finer grade, and a sander 29 for sanding the surfaces outside of the scoop or saddle. All of these different tools are rotated at a speed common to such tools, and each is carried by similar mechanisms. The posts 31 extend upwardly from the side frames 1. A cross piece 32 is journaled in bearings 30 at the upper ends of the 10 posts 31. Rock arms 33 are fixed on the cross pieces 32 and extend forwardly having the bearings 33^a for the shafts 34 carrying the several tools above mentioned. These shafts 34 are provided with the drive pulleys 24^a, 25^a, 26^a, 27^a, 28^a and 29^a corresponding with the several tools and each of these are connected by belts to a single drive pulley 35 mounted on the drive shaft 36, the outer belts running over the inner belts as clearly 20 shown in Fig. 9.

Supporting arms 37 extend downwardly from the rock arms 33. These are extended through the rock arms and have their upper ends screw threaded, the lower part as it 30 enters the rock arms being squared to prevent turning. Nuts 38 having worm gears on their outer peripheries are screwed onto the upper ends of the supporting rods 37. These are held in place by the lugs 39. 35 Worms 40 engage the worm gears on the nuts 38. The worms 40 are carried by the rods 41 extending across the head so that the two worms 40 at each side of the machine operate together. The rods are provided by 40 a crank 42 by which it may be turned to adjust the supporting rod 37. By this mechanism it will be noted that the supporting rods at each side of the head work together, the worms and nuts forming a paralleling 45 device for this purpose. Rollers 43 are arranged on the heads utilized for forming the scoops and rollers 44 are arranged on the rods 37 for the heads that are utilized for forming the saddle. Pattern tracks 45 and 50 46 are arranged along the sides of the carrier in the path of the rolls 43 and 44. The pattern tracks supporting the rolls 43 and 44 respectively, and consequently supporting the heads to which the rods 37 are attached. 55 The desired patterns are formed in these tracks as shown, these patterns are the long depressions 45^a for the scoop and the double depression 46^a for forming the saddle. The rolls 43 forming the scoop travel on the outer 60 track 45, and roll 44 on the inner track.

The blanks are positioned on the carrier relatively to the pattern as desired. When a blank opposite the pattern 45^a reaches the head having the cutter 24, the rolls 43 enter 65 the depression 45^a so that the cutters 24 are

allowed to drop sufficiently to form the scoop in the seat, and when the same blank reaches a position opposite the saddle cutter or head 25 the rollers 44 which are arranged to travel over the track 46 follow into the grooves or 70 depressions 46^a and form the saddle. The sanding rolls operate in a similar manner each following the pattern just as the cutters do. The sand roller 29 is supported by the roller 43^a, and while the sand roll may support the heads sufficient for the flat surfaces, I prefer to allow the roll 43^a to ride directly 75 in the plates 46, so that it may be adjusted as desired.

The shaft 11 has the drive pulley 47 arranged upon it, and this is driven from a pulley 49 on the shaft 36 by means of the belt 48. It is desirable, that the carrier, and the different heads be driven from the same source of power, so that when one is properly 85 speeded any variation of speed in one involves the same variation in the other.

What I claim as new is.

1. In a wood working machine, the combination of an endless carrier; a track mounted 90 on the carrier at its side and having a plurality of similar patterns along the line of the track formed of raised and depressed portions relatively to the path of movement of the carrier; a plurality of wood working 95 heads comprising a shaping head and a finishing head of the same pattern; movable mountings for said heads; supports for said mountings, said supports resting on said track, each pattern of the track successively 100 engaging the respective supports of the mountings for the shaping and finishing cutters to give the same pattern movement to both cutters to and from the path of the carrier and at right angles to the axes of the cutters and operating each support independently of the movement or position of any other support.

2. In a wood working machine, the combination of an endless carrier; a plurality of 110 tracks mounted on the carrier at its side, each track having a plurality of similar patterns along the line of the track formed of raised and depressed portions relatively to the path of movement of the carrier, the patterns of one track differing from those on the other track; a plurality of wood working 115 heads comprising a shaping head and a finishing head of the same pattern; movable mountings for said head; supports for said 120 mountings operating on one of said tracks, each pattern of this track successively engaging the respective supports of the mountings for the shaping and finishing cutters to give the same pattern movement toward and 125 from the path of the carrier and at right angles to the axes of the cutters and operating each support independently of the movement or position of any other support; a wood working head of different pattern; a mov- 130

able mounting for said head; and supports for said mounting operating upon the other of said tracks.

3. In a wood working machine, the combination of an endless carrier; a plurality of tracks mounted on the carrier at its side, each track having a plurality of similar patterns along the line of the track formed of raised and depressed portions relatively to the path of movement of the carrier, the patterns of one track differing from those on the other track; a plurality of wood working heads comprising a shaping head and a finishing head of the same pattern; movable mountings for said head; supports for said mountings operating on one of said tracks, each pattern of this track successively engaging the respective supports of the mountings for the shaping and finishing cutters to give the same pattern movement toward and from the path of the carrier and at right angles to the

axes of the cutters and operating each support independently of the movement or position of any other support; a second series of wood working heads comprising a shaping cutter and a finishing cutter of the same pattern; movable mountings for the second series of heads; supports therefor resting on the other of said tracks, the patterns thereof successively engaging the supports for the second series of heads to give the same pattern movement to said second series of heads toward and from the path of the carrier and at right angles to the axes of the heads.

In testimony whereof I have hereunto set my hand in the presence of two subscribing witnesses.

HARRY B. RANDALL.
